UNITED STATES PATENT OFFICE.

ALEXANDER MILNE TROUP, OF SANFORD, NORTH CAROLINA, ASSIGNOR OF ONE-HALF
TO JUNE U. GUNTER, OF SANFORD, NORTH CAROLINA.

PHOTOGRAPHIC-PRINTING APPARATUS.

1,323,559.

Specification of Letters Patent.

Patented Dec. 2, 1919.

Application filed February 18, 1918. Serial No. 217,820.

To all whom it may concern:

Be it known that I, ALEXANDER MILNE TROUP, a citizen of the United States, residing at Sanford, in the county of Lee, 5 State of North Carolina, have invented certain new and useful Improvements in Photographic-Printing Apparatus, of which the following is a description, reference being had to the accompanying drawings, forming a part hereof.

This invention relates to a photographic printing apparatus and particularly to a construction adapted for use in rapidly printing from the negative either by natural or artificial light.

The invention has for an object to provide a novel and improved construction in which a nonactinic shutter is formed to normally close a light opening and to be actuated by a pivotally mounted printing frame to remove the shutter as the frame is swung into position at said opening for printing purposes.

A further object of the invention is to 25 provide a novel and improved means by which printing may be performed by artificial light and comprises a boxing having a printing opening and means for illuminating the boxing together with a nonactinic 30 shutter mounted within the boxing to normally close said opening and a printing frame constructed and arranged to remove said shutter from the opening as it is placed in printing position.

A further object of the invention is to 35 provide a novel and improved construction of printing frame in which the negative is supported upon a seat so that its inner face is flush with the lower edge of the frame, in 40 connection with a contact board adapted to close the frame, so that when said board is opened the print paper held against the negative will be free to drop through the cut-away portion at the lower edge of the 45 frame and thus avoid any handling thereof in its removal from the frame.

Other objects and advantages of the invention will be hereinafter set forth and the novel features thereof defined by the 50 appended claims.

In the drawings:—

Figure 1 is an elevation of the inner face of the apparatus.

Fig. 2 is a vertical section on the line 55 2—2 of Fig. 3.

Fig. 3 is a central horizontal section and Fig. 4 is a vertical section on the line 4—4 of Fig. 3.

Like numerals refer to like parts in the several figures of the drawings.

The numeral 10 designates a casing which may be of any desired construction or configuration and at the inner face thereof a shutter 11 is movably mounted, preferably by means of spring hinges 12 at its lower edge, by which the shutter is normally retained in closed position. This shutter may be of any preferred character to prevent the transmission of active photographic rays to the face of the printing frame 13, for instance it may be glazed with nonactinic material as at 14.

The printing frame 13 may be mounted on, the casing 10 during the printing operation for instance by means of a hinge or joint 15 at one side of the printing casing. This frame is provided with a seat or groove 16 of substantially equal thickness with a glass negative as indicated at 17 so that when the negative is seated therein it lies flush with the lower edge 18 of the frame. If desired the molding 19 about the frame is omitted at this edge for the purposes to be herein-after described. The frame is also provided with a closure board 20 having an operating handle 21. This board may be pivotally mounted upon the frame as at 22 and formed in sections connected by a hinge 23 as is usual in printing frames.

For the purpose of actuating the shutter 90 to open the same as the printing frame is swung into position within its casing actuating means are provided to engage the shutter and preferably comprise the roller 24 mounted on the frame and adapted to 95 engage an angular track 25 carried upon the inner face of the shutter by this construction the inner movement of the printing frame swings downward the nonactinic shutter thus permitting the operation to 100 proceed.

When it is desired to print by artificial light a casing or boxing 26 may be provided to inclose the shutter and any suitable means for producing artificial light located therein 105 as indicated at 27.

In the operation of the invention the shutter is normally held in closed position when the printing frame is swung away therefrom as shown in Fig. 3. The negative 110

may then be easily placed upon the seat of the frame with its lower edge flush with the face of the frame as shown in Fig. 4. The usual printing paper is then inserted and the closure board placed in position as indicated by full lines in Fig. 3. Pressure upon the handle of this board carries the frame inward and an actuating roller thereon engages the track upon the shutter to swing 10 the same into open position and permit the active printing rays of light to contact with the frame. When the frame is removed after the printing operation the shutter is automatically closed and as the board is 15 swung outward into the outward position as shown in Fig. 3 the print paper drops directly downward through the cut-away portion of the frame at its lower edge. This permits of a very efficient and rapid printing 20 operation and avoids the injury to the print by contact of the fingers therewith in removing it from the frame. The invention may be used in the wall of a dark room or any other position, while if it is desired to print 25 by artificial light the illuminating boxing surrounding the shutter prevents the action of this light except at such time as the frame is in proper position for printing.

It will be seen that this construction provides means by which the active light rays are cut off from the frame by the shutter at all times when the frame is not in printing position and the operator may thus conveniently handle the paper without damage 35 of exposing the same before it is placed in printing position or after its removal therefrom.

While the invention has been described in connection with the use of a glass negative

it is also adapted for printing from films in 40 which case a clear glass may be mounted in the frame as a support for the film.

This invention provides a simple, efficient and economically constructed means for photographic printing and when adapted 45 for use of either professional photographers or amateurs.

What is claimed is:—

1. In a photographic printing apparatus, a pivoted nonactinic shutter, a track thereon, a pivoted printing frame opposite said shutter and means upon said frame to engage said track to open the shutter. 50

2. In a photographic printing apparatus, a pivoted nonactinic shutter, a track thereon, a pivoted printing frame opposite said shutter and a roller mounted upon said frame to traverse said track in the opening movement of said shutter. 55

3. In a photographic printing apparatus, 60 a pivoted nonactinic shutter, a track thereon, a pivoted printing frame opposite said shutter and a spring means for normally retaining the shutter in closed position.

4. In a photographic printing apparatus, 65 a casing provided with a light opening, a shutter pivoted at one edge to cover said opening, spring means to normally close said shutter, a printing frame pivoted at one edge opposite said opening, an angular track disposed upon said shutter, and an actuating runner to engage upon said track. 70

This specification signed and witnessed this fourth day of Feb. A. D. 1918.

ALEXANDER MILNE TROUP.

In the presence of—

EDWARD R. BUCHAN,
WARREN R. WILLIAMS.
